COMBINED CABINET AND DESK

Patrick V. Gallo, Brooklyn, N. Y.

Application August 16, 1950, Serial No. 179,805

1 Claim. (Cl. 312—317)

1

This invention relates to a combined cabinet and desk wherein the desk is housed within the cabinet and may be readily extended to full length beyond the cabinet.

It is an object of my invention to provide an article of furniture of the character described which is simple to construct, and occupies a minimum amount of space.

It is a further object of my invention to provide an article of furniture of the character described wherein the forward legs of the desk form a decorative edge at the forward extremity of the cabinet.

It is another object of the invention to provide an article of furniture of the character described wherein a plurality of compartments are made available upon lifting of the desk top panel.

It is a further object of the invention to provide an article of furniture of the character described wherein the desk may be used in extended or collapsed position, and is further adapted in one position, to provide a blackboard or mirror.

With the above and other objects in view, the invention includes certain novel details of construction and combinations of elements herein more fully described and claimed, and I desire it understood that various modifications will be apparent to those skilled in the art without departing from the spirit or scope of the invention as set forth in the appended claim.

In the accompanying drawing forming a part of this application:

Figure 1 is a view in perspective of the invention showing the desk in dotted extended position.

Figure 2 is a fragmentary section taken along line 2—2 of Figure 1.

Figure 3 is a fragmentary view of the invention similar to Figure 1 showing the top front panel extended and the rear panel upright.

Figure 4 is a sectional view taken along the line 4—4 of Figure 3.

Figure 5 is a fragmentary section of an alternate construction embodying the invention.

Figure 6 is a fragmentary section taken along the line 6—6 of Figure 5.

Referring to the drawings in detail, the cabinet includes a pair of side walls 10a and 10b and cross members or shelves 12 and 14 extending between and retaining said side walls in spaced relation to one another. To strip panels 16a and 16b are secured to side walls 10a and 10b respectively and extend above the respective side walls to form a portion of a hinge member to be hereinafter described.

A first top rear panel 18 is formed to fit over

2

side walls 10a and 10b and is hinged with respect to panels 16a and 16b by means of a dowel 19 which is limited in movement to an inclined upward or downward direction in a recess such as 20 formed in panels 16a and 16b.

The dowels 19 may be secured in top rear panel member 18 or in a peripheral member such as 22 to permit the hinging of panel 18 with respect to panels 16a and 16b. A second top front panel 24 is provided with front legs 26a and 26b secured thereto and is movable with respect to side walls 10a and 10b in such manner that panel 24 may be stacked respective panel 18 in a closed position and may be drawn out so that the rear edge terminus of panel 24 coincides with the forward edge of panel 18.

Panel 24 is further provided with side bracing members such as 28 and a front brace member 30. Retention of top member 24 in a proper relation to member 18 and side walls 10a and 10b is obtained by forming an inverted T shape channel 32 in side members 10a and 10b and includes a dowel 34 which is attached to brace member 28 and rides in the head of the T section 32, as more fully shown in Figure 4. Top member 24 may be removed if desired.

For the purpose of utilizing as much of the available space as permissible a hidden drawer 36 is formed under top member 18 and under top member 24 when said member is in a closed position.

The top member 18 may be formed with a blackboard 38 on the under side thereof or may be provided with a mirror to permit the use of the cabinet as a small vanity.

An alternate construction is illustrated in Figures 5 and 6 wherein solid side walls 10x and 10y are shown as corresponding to the side walls 10a and 10b. Hinging of top member 18x, to the side walls is obtained by forming a groove 20x in said side wall and providing top member 18x with a dowel 19x which is adapted to move within the confines of recess 20x, as illustrated in Figures 5 and 6.

The embodiment illustrated in Figure 5 similarly shows one of a pair of doors which may be used with my invention in place of open shelving.

In operation reference is made to Figure 1 wherein my combined cabinet and desk are in closed position. To extend the desk it is merely necessary to pull out top member 24 by grasping and pulling on member 30, permitting top member 18 to fall into the place previously occupied by member 24, and thus forming a writing area having the combined cross sectional area

of both top members 18 and 24. To close the cabinet and desk, it is merely necessary to raise top member 18x slightly and permit member 24 to slide thereunder.

Access to drawer 36 is obtained by extending the desk and raising top member 18.

In carrying out the invention, use of legs, having the characteristics of mouldings have permitted the assembly of a neat and compact unit.

Having thus fully described an illustrative embodiment including my invention, what is claimed is:

A cabinet comprising a pair of side walls, a plurality of cross members extending between said side walls and adapted to maintain said side walls in fixed space relation, a first top member and a second top member, means hinging said first top member to said side walls, a pair of legs secured to said second top member, a pair of oppositely

disposed inverted T channels formed on the inside of said respective side walls, a pair of projections secured to opposite sides of said second top member and slideably mounted within said channels respectively, said first and second top members forming a continuous surface in extended position, and said first member stacked above said second member in closed position.

PATRICK V. GALLO.
